Primary Examiner — Clint A Samuel(74) *Attorney, Agent, or Firm* — LAUBSCHER & FRETWELL, P.C.(57) **CLAIM**

The ornamental design for a lamp, as shown and described.

DESCRIPTION

FIG. 1 is a top front perspective view of first embodiment of a lamp according to our invention;

FIG. 2 is a front elevation view of the lamp of FIG. 1;

FIG. 3 is a rear elevation view of the lamp of FIG. 1;

FIG. 4 is a left side elevation view of the lamp of FIG. 1;

FIG. 5 is a right side elevation view of the lamp of FIG. 1;

FIG. 6 is a top plan view of the lamp of FIG. 1;

FIG. 7 is a bottom plan view of the lamp of FIG. 1;

FIG. 8 is a top front perspective view of second embodiment of a lamp according to our invention;

FIG. 9 is a front elevation view of the lamp of FIG. 8;

FIG. 10 is a rear elevation view of the lamp of FIG. 8;

FIG. 11 is a left side elevation view of the lamp of FIG. 8;

FIG. 12 is a right side elevation view of the lamp of FIG. 8;

FIG. 13 is a top plan view of the lamp of FIG. 1; and,

FIG. 14 is a bottom plan view the lamp of FIG. 1.

The broken lines in the drawings are for the purpose of illustrating portions of the lamp and forms no part of the claimed design.
